Primary Examiner — Katie Jane Stofko*(74) Attorney, Agent, or Firm* — Ryan T. Grace; Advent, LLP**CLAIM**

The ornamental design for a cut potato product, as shown and described.

DESCRIPTIONFIG. 1 is an isometric view of a cut potato product.
FIG. 2 is another isometric view of the cut potato product of FIG. 1.

FIG. 3 is a top plan view of the cut potato product of FIG. 1.

FIG. 4 is a bottom view of the cut potato product of FIG. 1.
FIG. 5 is a front elevation view of the cut potato product of FIG. 1.

FIG. 6 is a rear elevation view of the cut potato product of FIG. 1.

FIG. 7 is a left side elevation view of the cut potato product of FIG. 1; and,

FIG. 8 is a right side elevation view of the cut potato product of FIG. 1.

Portions of FIGS. 1 through 8 are shown in dash-dot-dash boundary lines illustrating portions of the article that form no part of the claimed design.
